UNITED STATES PATENT OFFICE.

ELNER H. SHAW, OF CLAY CENTRE, KANSAS.

ICE-CREAM FREEZER.

SPECIFICATION forming part of Letters Patent No. 428,148, dated May 20, 1890.

Application filed December 19, 1889. Serial No. 334,265. (No model.)

To all whom it may concern:

Be it known that I, ELNER H. SHAW, a citizen of the United States, residing at Clay Centre, in the county of Clay and State of Kansas, have invented a new and useful Ice-Cream Freezer, of which the following is a specification.

This invention has relation to ice-cream freezers; and among the objects in view are to produce a cheap and simple freezer designed to rapidly freeze the cream, and this with a reduced amount of refrigerative agent, thereby effecting a saving in the cost of the same and the time and labor usually expended in operating the freezer.

With these general objects in view the invention consists in certain features of construction, hereinafter specified, and particularly pointed out in the claims.

Referring to the drawings, Figure 1 is a perspective of a freezer constructed in accordance with my invention. Fig. 2 is a similar view, the cover thrown back. Fig. 3 is a vertical longitudinal central section; Fig. 4, a perspective of the rotary freezing-cylinder; Fig. 5, a similar view of the stationary freezing-chamber; Fig. 6, a perspective of the delivery-blade.

Like numerals of reference indicate like parts in all the figures of the drawings.

1 represents a chest of suitable dimensions, which is supported by suitable legs 2, and to one edge of the chest there is hinged the cover 3, the free edge of which is provided with hooks 4 for engaging the eyes 5, inserted in the chest in line with the hooks, whereby said cover may be temporarily locked in a closed position. The opposite longitudinal sides of the chest 1 are each provided with an open bearing 6.

7 represents the rotary freezing-cylinder, and the same is provided with opposite conical ends 8, from which projects stub-shafts 9, taking into the bearings 6, one of said shafts 45 being bent to form a crank-handle 10, whereby the cylinder may be revolved. The central periphery of the cylinder is provided with an inwardly-disposed annular channel 11, and at one side of the same there is provided an opening 12, covered by a screw-cap 13, by which the refrigerative agent, preferably crushed ice, is introduced within the cylinder.

14 represents a stationary oblong ice-chamber inserted between the opposite walls of the reduced channel and the ends walls of the 55 chest, that wall of the chamber adjacent to the channel being concaved or semi-cylindrical and adapted to embrace the cylinder for about one-half its circumference, and form between the same and the channel a narrow 60 space. The upper end of the stationary chamber is provided with an opening 15, at the opposite sides of which are ways 16, into which is slid a removable cover 17.

A recess 18 is formed in one of the end walls 65 of the chest and opposite to the stationary refrigerative-chamber 14, and mounted within the recess is a scraper or delivery blade 19, the rear end of which protrudes from the opening out of the chest and the front end of 70 which extends into the chest and against the reduced channel of the refrigerative cylinder. The blade is of a width agreeing with the channel and has its lower edge snugly pressed thereto by means of a coiled spring 20, which 75 connects the rear extremity of the blade with the end walls of the chest.

21 represents a cross-bar mounted between the opposite side walls of the chest and resting upon the blade, and serving to maintain 80 the same in proper relation with the rotary cylinder.

22 represents a cream-feeding can, from the bottom of which there depends a conical spout 23, which takes into an opening 24 of corresponding shape formed in the hinged cover 3 and directly over the channel of the cylinder. The upper end of the feeder is provided with a removable cover 25, in which is formed an opening 26, and through the opening and depending into and closing the conical spout is a rod 27, provided at its lower end with a conical valve plug or head 28.

The operation of my invention is as follows: The rotary cylinder and the stationary 95 ice-chamber are both filled with the refrigerative agent and the cream-feeder mounted in position upon the hinged cover. The rotary cylinder is now rotated to the right by means of the crank-handle and the rod 27 raised to 100 permit the cream to flow from this feeder upon the channel formed in the revolving cylinder, which cream is carried in a thin sheet around and between the semi-cylindrical face or side

walls of the stationary refrigerator-tank and to the delivery-blade 19, which scrapes the cream from the surface of the channel, and the same falls through an opening 30, formed 5 in the bottom of the chest. By this construction it is apparent that the cream will be thoroughly frozen in a very short space of time and with a minimum amount of refrigerative agent. By reason of the conical ends 10 of the rotary freezing-cylinder the freezing medium or agent is all thrown to the center of the cylinder and surrounds the reduced channel, whereby the full effect of the same is transmitted to the thin layers of cream as 15 they pass around the cylinder.

The stationary refrigerating-chamber may be removed for cleaning purposes, &c., by revolving the same partially to the left and elevating. The rotary cylinder may also be 20 removed for similar purposes by first removing the stationary chamber and then lifting the cylinder from its bearings.

It is apparent that by a freezer thus constructed either large or small quantities of 25 cream may be frozen at a time and the device is adapted for both retail and wholesale.

Having thus described my invention, what I claim is—

1. In an ice-cream freezer, a receptacle, a 30 rotatable freezing-cylinder mounted therein and provided with a channel, a scraping-blade terminating in the channel, and a stationary freezing-chamber embracing the cylinder, all combined and operating substantially as 35 specified.

2. In an ice-cream freezer, a rotating refrigerative-receptacle of cylindrical shape and having opposite conical ends, and an intermediate cream-receiving channel, in combination with a freezing-chamber embracing the channel portion of the cylinder, substantially as specified.

3. The combination, with a receptacle, a ro-

tating refrigeratiye-cylinder provided with a peripheral channel mounted in the same, of 45 a refrigerating-chamber mounted on one side of and embracing the channel portion of the cylinder, and a cream-feeding can mounted above the cylinder and having a spout adapted to deliver cream within the channel 50 of the same and directly in front of the chamber, substantially as specified.

4. In an ice-cream freezer, the combination, with a receptacle and a rotatable freezing-cylinder having the peripheral channel, of a 55 stationary freezing-chamber mounted in the receptacle at one side of the cylinder and having a semicircular concaved side wall loosely embracing the cylinder and combining therewith to form an intermediate channel, substantially as specified.

5. The combination, with the chest 1, having an opening in its bottom, and the hinged cover having the opening 24, of the freezing-cylinder removably mounted in the chest and 65 provided with an operating-crank, and provided with a central peripheral channel, a scraper-blade terminating in the channel, a stationary ice-chamber located at the opposite end of the chest and of a width corresponding with the channel and having its side 70 wall concaved to embrace the channel and located a slight distance from the same, and the cream-receptacle mounted on the hinged cover and having a spout inserted through 75 an opening in the same and arranged over the channel, and a valve-plug mounted in the spout, substantially as specified.

In testimony that I claim the foregoing as my own I have hereto affixed my signature in 80 presence of two witnesses.

ELNER H. SIAW.
